UNITED STATES PATENT OFFICE.

SIMON L. WALDMAN, OF BOSTON, MASSACHUSETTS, ASSIGNOR TO WALDMAN & DANIELS, OF SAME PLACE.

LEGGIN.

SPECIFICATION forming part of Letters Patent No. 276,737, dated May 1, 1883.

Application filed March 5, 1883. (No model.)

To all whom it may concern:

Be it known that I, SIMON LAZER WALDMAN, a citizen of the United States, residing at Boston, in the county of Suffolk and State of Massachusetts, have invented certain new and useful Improvements in Leggins; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

This invention has reference to leggins adapted to general use, though perhaps more especially to ladies' use, and are equally well applicable to sportsmen's needs.

My invention consists in a leggin having its instep of one piece, or intact, and permanently closed up, while its leg portion is open and secured together by buttons or clasps in the usual manner.

Heretofore leggins have been open the entire length, and frequent annoyance is met in the lower buttons becoming torn away, injuring the garments and requiring to be sewed on, as well as exposing the foot of the wearer to moisture and dirt.

In my invention I permanently close the lower part of the leggin, and secure the remainder by buttons or other fastenings, as heretofore stated. When about to be used, I simply thrust the foot through the perma-

nently closed portion, and then button up the slit or open part of the leggin. In doing this I prevent detachment of the lower buttons, and, in fact, the upper ones, as the upper ones seldom become lost until the lower ones are detached. For this reason the annoyance and labor of frequently sewing on buttons are avoided. The instep portion of the leggin fits neatly and tightly and excludes snow, moisture, and dirt more effectually than if buttoned.

The drawing accompanying this specification represents a view of a leggin containing my improvement.

In this drawing, A represents a leggin of ordinary form and construction, with the exception of the instep portion being closed.

In carrying out my invention I permanently secure or close the instep portion of the gaiter, as shown at B, the flap C above such point of union being buttoned or otherwise connected to the body portion.

I claim—

A leggin the instep portion of which is permanently closed, while above it the leg is open and adapted to be closed by buttons or other means, substantially as herein described.

In testimony whereof I affix my signature in presence of two witnesses.

SIMON LAZER WALDMAN.
